UNITED STATES PATENT OFFICE.

JOSEPH WM. SHARP, OF PHILADELPHIA, PENNSYLVANIA.

GAS BURNER.

Application filed April 11, 1921. Serial No. 460,221.

To all whom it may concern:

Be it known that I, JOSEPH W. SHARP, a citizen of the United States, residing at Philadelphia, in the county of Philadelphia and State of Pennsylvania, have invented certain new and useful Improvements in Gas Burners, of which the following is a specification.

This invention relates to stoves and furnaces, and the primary object of the invention is to provide an improved means for converting an ordinary coal burning stove or furnace into a gas burning stove or furnace, so as to eliminate the inconveniences generally experienced with the caretaking of coal burning stoves and furnaces.

Another object of the invention is to provide a novel burner for use in ordinary coal burning stoves, and a novel means for protecting the burner, said means being formed of fire brick or other refractory material, so as to form means for effectively radiating heat from said burner.

A further object of the invention is to provide a novel means for mounting the improved burner within the furnace or other coal burning stove, a novel grate arranged around the burner, and a novel means for supporting fragments of refractory material, so as to form a heat radiating unit.

A still further object of the invention is to provide an improved gas burner of the above character, which will be durable and efficient in use, one that will be simple and easy to manufacture, and one which can be placed upon the market and incorporated with any stove at a reasonable cost.

With these and other objects in view, the invention consists in the novel construction, arrangement and formation of parts, as will be hereinafter more specifically described, claimed and illustrated in the accompanying drawings, forming a part of this specification, in which:

Figure 1 is a fragmentary vertical section through an ordinary coal burning furnace showing the novel type of burner arranged therein, the novel grate and protector therefor, and the bed of heat radiating material.

Figure 2 is a fragmentary horizontal section through a furnace showing the improved burner and grate incorporated therewith.

Figure 3 is a fragmentary transverse sec-

tion through a coal burning cook stove, showing the novel type of burner and grate incorporated therewith.

Figure 4 is a fragmentary longitudinal section through a cook stove, showing a novel type of burner and grate incorporated therewith.

Referring to the drawings in detail, wherein similar reference characters designate corresponding parts throughout the several views, the letter A indicates a furnace; B, a novel type of gas burner for use therewith; C the grate or protector for the burner and D the bed of heat radiating material supported by the grate.

The furnace A may be of the usual or any preferred type, and has merely been shown for illustrating the use of the invention, and it is to be understood that the attachment is adapted to be used with any type of coal burning stove or furnace, for converting the same into a gas burning stove or furnace. As shown the furnace A includes the usual casing or wall 5 provided with the usual fire door (not shown), and ash door 6.

The inner surface of the wall 5 may be provided with an annular flange 7 for supporting the novel type of grate C which will be hereinafter more fully described. The ash door 6 may be provided with the usual draft slide 8, for controlling the draft in the furnace.

The burner B is preferably formed in two sections, an upper section 9 and a lower section or base 10. The lower section 10 as shown, includes a relatively large tubular body 11, which has its lower end open and flared outwardly as at 12. The lower flared end 12 of the tubular body 11 will have leading directly into the center thereof, the gas feed pipe 13, which may lead to any suitable source of supply. This pipe can have arranged therein an ordinary or any preferred type of gas valve 14 for controlling the flow of gas to said burner.

The upper section 9 includes a concavo-convex shaped plate 14, an annular depending side wall 15, a bottom wall 16, and a collar 17. The collar 17 receives the upper end of the tubular body 11, and may be detachably connected thereto by a suitable pin and bayonet slot connection. The upper wall 14 and the annular side wall 15 is provided with a plurality of outstanding burner nipples 18,

which are adapted to extend at all angles from the said walls, so as to direct the flame from the burner in all directions.

The body or burner 9 rests upon or supports a ring 20, on which the grate bars 21 are adapted to rest. It is preferred that these grate bars be formed of refractory material, and the same are gradually tapered toward their inner ends so as to form a substantially circular disc flange. As shown, the outer ends of the grate bars rest upon the flange 7 and the inner ends thereof rest upon the ring or annular body 20. These grate bars 21 terminate short of the burner 15 B, and the burner is provided with a spaced protecting dome 22, which is also preferably formed of fire brick or other refractory material. As shown, the dome is formed of sections, so as to facilitate the placing thereof 20 in the furnace, and the lower edge of the outermost sections rest upon the upper surface of the fire bricks 21 at the inner edge thereof. The protecting dome 22 in reality forms a portion of the grate C, and the bars 25 21 and the dome 22 supports the bed of refractory material D.

This bed of refractory material D may be formed of broken fire brick or the like, and will be heaped upon the grate bars 21 and 30 the dome 22 to the desired height. It can be seen that the burner B will heat the fire brick, which will in turn heat the bed of refractory material D, which will effectively radiate the heat. It also can be seen that 35 the bed of refractory material D will become red hot and glow similar to an ordinary coal fire. In order to support combustion the air will be mixed with the gas in the tubular body 10 and the gas will flow in through the 40 lowered flared end thereof. The amount of air taken into the lower flared end of the tubular body can be controlled in any preferred manner, and if so desired the draft slide 8 of the ash door 6 can be utilized for 45 this purpose.

While the burner shown in Figures 1 and 2 has been especially adapted for furnaces, particularly of the hot air type, the burner can be readily used for cook stoves, and in 50 Figures 3 and 4 is shown a particular type of burner grate, which is adapted to be used with cook stoves.

In these figures, the cook stove may be of the usual or any preferred construction 55 as indicated by the letter E and has arranged therein a novel burner F, the grate G and the bed of refractory material H. The stove, as stated, is of the ordinary or any preferred construction and includes the side walls 25, and front and rear walls 26 and 27. The front wall 26 may be provided with the usual fire door (not shown) and the ash pit door 28 which can be provided with the usual draft slide 29.

60 The burner F in this construction is pref-

erably of elongated form, so as to extend under all of the cook holes in the stove, and this burner includes a longitudinally extending body 30 having the dome 31 formed at the forward end thereof. The dome 31 is provided with a lower flared end 32, which terminates adjacent to the ash pit door 28. The ends of the longitudinal body 30 may be provided with lugs or strength ribs 33 or 34 and it can be seen that the lug or strength rib 34 extends beyond the dome 31. The lugs 33 and 34 may be detachably fitted in the usual sockets 35, formed on the stove for supporting the ordinary grate. The longitudinally extending body 30 is provided with 70 rows of outwardly extending burner nipples 36, and it can be seen that the burner throughout its entire length with the exception of the dome 31 is provided with the burner openings or nipples. 75

The grate C includes the transversely extending grate bars 37, which are preferably formed of fire brick, and as shown these grate bars are relatively narrow and elongated in form and extend inwardly from the side walls 25 of the stove toward the burner F and the inner ends of these grate bars rest upon the longitudinally extending supporting bars 38 which may have their terminals anchored respectively in the front and rear walls 26 and 27 of the stove. The outer ends of the grate bars 37 rest upon suitable longitudinally extending flanges or ribs 39 formed on the walls 25 of the stove. A suitable longitudinally extending dome 40 is also provided in this form for protecting the burner F and includes the longitudinally extending fire bricks 41, and as shown these fire bricks have their side edge preferably tapered, so that the dome may be curved transversely, as clearly shown in Figure 3 of the drawings. It can be seen that the free edges of the lower fire bricks 41 rest upon the grate bars 37 of the grate. 90

The bed of refractory material H is placed 100 upon the dome 40 and the grate G in the same manner as is shown in Figures 1 and 2 and this bed of refractory material is adapted to become hot and radiate heat throughout the entire upper surface of the stove. The lower flared portion of the dome 31 is of course open, and has extending thereinto the fuel feed pipe 43, which may be provided with a suitable gas cock 44. It can be seen that the gas and air will be intermixed 105 in the dome 31. The flow of air in this form may also be controlled in any manner, but it is preferred that the slide door 29 be used in the ash pit 28. 110

From the foregoing description, it can be 115 seen that an exceptionally simple burner and grate has been provided for permitting an ordinary coal burning stove or furnace to be 120 easily and readily converted into a gas stove or furnace. This effectively solves the prob- 125 130

lem of fuel and entirely eliminates the inconveniences associated with the taking care of coal burning stoves.

Changes in details may be made without departing from the spirit or scope of this invention; but,

I claim:

1. The combination of a burner comprising a head provided with a plurality of burner openings, a supply pipe leading to said head, a grate arranged around the head formed of refractory material, and a dome formed of refractory material supported by said grate and arranged over and in spaced relation to said head.

2. The combination of a burner comprising a head having a plurality of burner openings formed therein, a sectional grate formed of fire brick surrounding the head, a dome supported by the grate formed of sections of refractory material arranged above and in spaced relation to said head, and a bed of refractory material arranged upon said grate and said dome.

3. The combination with a burner comprising a head having a plurality of outlet burner openings therein, an enlarged tubular body communicating with the head having a lower open flared end, a gas supply pipe extended into said flared end, means controlling the flow of gas through said pipe, a plurality of grate bars of refractory material arranged outwardly of the head, and a dome formed of sections of refractory material arranged upon and supported by the grate bars and arranged over the head and in spaced relation thereto.

4. A gas burner for use in connection with coal burning stoves and furnaces comprising a burner head having a plurality of burner openings formed therein, a tubular body communicating with the head having an open flared end, a gas supply pipe leading into said flared end, a sectional grate arranged around the burner head, and a sectional dome carried by the grate and arranged over and in spaced relation to the burner head, the dome and grate being

formed of refractory material, and fragments of refractory material supported by said dome and grate arranged to be heated from the flame from said burner head.

5. The combination with an ordinary coal burning stove or furnace, of a gas burner therefor including a head arranged centrally within the stove, a grate of refractory material supported by said stove and arranged about the head, a dome of refractory material surrounding said head and arranged over and in spaced relation to said head carried by the grate, said dome being formed of refractory material, and a bed formed of fragments of refractory material supported by said grate and said dome.

6. The combination with a coal burning stove including an ash pit door having a draft slide therein, of a gas burner for the coal burning stove including a burner head having a plurality of outlet burner openings therein, and a tubular body having a lower flared open end arranged adjacent to the ash pit door, a refractory grate and dome arranged around and over said burner head, a gas supply fuel pipe extending into the stove and into the lower flared end of the tubular body, a cut off valve arranged in said pipe, the draft slide forming means for regulating the amount of air taken into the flared end of said body.

7. The combination with an ordinary coal burning stove including a casing, and a supporting flange carried by the side walls of the casing, of a gas burner therefor including a head arranged centrally within the casing, a supporting flange carried by the head, the head having a plurality of burner outlet openings formed therein, a grate of refractory material including a plurality of plates disposed in abutting relation and resting upon the supporting flanges carried by the head and by said casing and terminating at said head, and a dome formed of refractory material disposed over said head and resting upon the inner terminals of said grate.

JOSEPH WM. SHARP.
